(57) CLAIM

The ornamental design for a floor register trap as shown and described.

DESCRIPTION

FIG. 1 is a perspective view of a floor register trap;
FIG. 2 is a bottom perspective view thereof;
FIG. 3 is a bottom perspective view of the floor register trap shown in a configuration of use;
FIG. 4 is a top perspective view of the floor register trap shown in a configuration of use;
FIG. 5 is a top perspective view of the floor register trap shown in a configuration of use;
FIG. 6 is a top perspective view of the floor register trap shown in a configuration of use;
FIG. 7 is a front elevation view of the floor register trap (the opposite side being a mirror image);
FIG. 8 is a side view thereof (the opposite side being a mirror image);
FIG. 9 is a top plan view thereof; and,
FIG. 10 is a bottom plan view thereof.
The broken lines depict environmental subject matter and form no part of the claimed design.
